(57) **CLAIM**

The ornamental design for a case for electronic device, as shown and described.

DESCRIPTION

FIG. 1 is a front perspective view of a case for electronic device showing our new design, showing a stand of the case for electronic device in a closed state;

FIG. 2 is a rear perspective view thereof;

FIG. 3 is a front view thereof, showing cover plates in a retracted position;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front view thereof, showing cover plates in an extended position; and,

FIG. 10 is another perspective view thereof, showing the stand of the case for electronic device in an open state.

The broken lines depict portions of the case for electronic device that form no part of the claimed design.
